UNITED STATES PATENT OFFICE

160,459

AUTOMOBILE STONE SHIELD

Harry T. Bannister, Huntington Woods, Mich., assignor to Chrysler Corporation, Highland Park, Mich., a corporation of Delaware

Application August 18, 1949, Serial No. 4,572

Term of patent 7 years

(Cl. D14—6)

To all whom it may concern:

Be it known that I, Harry T. Bannister, a citizen of the United States, residing in the city of Huntington Woods, county of Oakland, and State of Michigan, have invented a new, original, and ornamental Design for an Automobile Stone Shield, of which the following is a specification, reference being had to the accompanying drawing, forming part thereof, in which:

Fig. 1 is a front elevation of the stone shield;

Fig. 2 is a side elevation of the stone shield, showing my novel design;

Figs. 3 and 4 are sectional views taken on the lines 3—3 and 4—4 respectively of Fig. 2; and

Fig. 5 is a side elevation of a stone shield, showing my new design, the broken line representation of an automobile fender being for illustrative purposes only.

I claim:

The ornamental design for an automobile stone shield, substantially as shown and described.

HARRY T. BANNISTER.
